UNITED STATES PATENT OFFICE.

THOMAS O'FLYNN, OF DAVIDSON, SASKATCHEWAN, CANADA.

VENTILATED WINDOW-SASH.

1,201,615.

Specification of Letters Patent. Patented Oct. 17, 1916.

Application filed December 2, 1915. Serial No. 64,620.

To all whom it may concern:

Be it known that I, THOMAS O'FLYNN, a subject of the King of Great Britain, residing at Davidson, Saskatchewan, Canada, have invented certain new and useful Improvements in Ventilated Window-Sashes, of which the following is a specification.

This invention relates to the class of wooden buildings, and more particularly to a ventilated window sash.

The object of my invention is to provide a window sash construction whereby any building or car may be properly ventilated by directing the incoming air toward the upper portion of the room or car, instead of directly upon the occupants as when the conventional type of window is raised from the bottom, or directly to the ceiling, as when the upper sash of the conventional type of window sash is lowered from the top. In the first instance, the direct draft of cold air is dangerous, and in the second instance the warm air which rises toward the top of an inclosed space is permitted to escape and the cold air to come in without that purifying of the atmosphere which can only be secured by constant agitation of the air, and which result is accomplished by the placing of my ventilator centrally of the window frame instead of either at the top or the bottom.

My ventilator is especially desirable for use in hospitals, schools, and railway cars, as well as all other buildings where a proper ventilation is desirable.

Furthermore, my device is extremely simple in construction and operation, effective for the purpose intended, and with the adjustment features so arranged that there will be no loose parts to rattle in an annoying manner, as occurs with the conventional type of window sash.

Other objects of this invention not at this time more particularly enumerated, will be clearly understood from the detailed description and drawings forming a part of this specification.

Furthermore, this invention consists in the novel arrangement and combination of parts more particularly described in the following specification and embodied in the claims appended hereunto and forming a part of this application.

Referring further to the drawings, which are merely illustrative of my invention: Figure 1 is a front elevation of the preferred

form of my ventilated window sash. Fig. 2 is a vertical section thereof. Fig. 3 is a vertical section of a modified form of my invention. Fig. 4 is a detail perspective view of a substitute member for certain parts shown in Figs. 2 and 3. Fig. 5 is a detail perspective view of another substitute member.

Referring further to the drawings wherein similar reference characters indicate similar parts through the respective views, 1 designates a window casing being so formed upon the lower half thereof as to receive an outside window 2 and screen 3, slidably mounted within the sides of said casing and an inside window 4 spaced apart from said outside window and screen, and slidably mounted within said casing, said inside window extending upwardly less than half the length of the casing. A window 5 for the upper half of the casing 1 is mounted within said casing intermediate the aforesaid outside window and screen and the inside window, its lower edge being adjacent the upper edge of said outside window. The central portion of the casing 1 is flared outwardly at 6, the top of said flared portion being arc-shaped and having ratchet notches 7 formed along the inner face near the top of said flared portion. A supporting strip 8 is interposed between the sides of said casing 1 adjacent the upper edge of the inside window 4. A window 9 is hingedly mounted at the bottom thereof upon said strip 8. The upper portion of the frame of said window 9 is provided with a pair of oppositely disposed pawls 10, adapted to engage with the ratchet notches 7, and to be maintained in engagement therewith by a coil spring 11 interposed between the handles 12 of said pawls.

From the construction as described, it is obvious that the hinged window may be opened to any desired degree and retained in a predetermined position by the engagement of the pawls with the ratchet notches. It is also apparent that the use of the screen is optional, and that in winter the screen would be removed and the conventional type of storm sash shown in Fig. 4 inserted. This change, however, would not depart from the principle of the double spaced lower windows having the ventilator as described.

As the window 2 is designed to keep out rain that might otherwise blow through the ventilator opening, and at the same time let in air through the screen 3, it may be found

desirable to substitute an angularly mounted window, as shown in Fig. 5, in the place of the window 2. Such a substitution would not only keep rain from blowing through the ventilator opening, but would also serve to direct a current of air upwardly through the open space at the bottom of said angularly mounted window, and through the ventilator opening.

10 In the modified form of my device shown in Fig. 3 of the drawings, I provide an angularly disposed window 13 fixedly mounted within the sides of said casing, the lower end of said window being placed adjacent the upper end of the inside window 4. A supporting strip 14 is interposed between the sides of the casing 1, spaced apart from and directly above the top of the window 4. A ventilator window 15 is hingedly mounted upon one edge thereof upon said strip 14, while a spring regulated pawl mechanism 16 is adapted to engage with ratchet notches 17 formed upon the inner faces of the arc-shaped flared portion 18, to maintain said 25 ventilator in a predetermined position. In other respects the modified form of my device is substantially similar to the preferred form thereof.

The utility, adaptability, and advantages 30 of my improved form of ventilated window sash being obvious, it is unnecessary to further enlarge upon the same herein.

Having now described and pointed out the new and useful features of my invention, I 35 do not limit myself to the shape of certain parts where the shape is not essential, nor do I restrict myself to the exact details of construction shown and described, but mean and intend to claim all equivalents and variations thereof, not departing in principle 40 from my invention, and falling within the purview of the appended claims.

What I claim as my invention and desire 45 to secure by Letters Patent is:

45 1. In a device of the character described, a window casing, a closure member mounted within the upper portion of said casing, a closure member mounted within the lower portion of said casing, a second closure mem-

ber mounted within the lower portion of 50 said casing in spaced apart relation with respect to said last aforesaid closure member, a supporting strip interposed between the sides of said casing, and a ventilator member hingedly mounted upon said supporting 55 strip.

2. A ventilated window sash consisting of a frame, an upper sash, lower sashes mounted in parallelism and spaced apart within said frame, a flared portion formed inwardly 60 upon the central portion of said frame, said flared portion formed with ratchet notches upon the inner face thereof, and means hingedly mounted upon said frame adapted to close the space between the outer extremity of said flared portion and the lower portion 65 of said upper sash.

3. A ventilated window sash consisting of a frame, a window mounted in the upper half of said frame, a closure member mounted in the lower half of said frame adjacent the outer portion thereof, a second window mounted in the lower half of said frame and spaced apart from said last aforesaid window, an inwardly flared portion formed 75 upon said frame centrally thereof, said flared portion being formed with ratchet notches upon the inner faces and adjacent the upper end thereof, a supporting strip mounted upon said frame, a ventilator window hingedly mounted upon said strip, and spring regulated pawls mounted upon said 80 ventilator window adapted to engage with said notches.

4. A ventilated window sash consisting of 85 a frame, an upper sash mounted in said frame, a lower sash mounted in said frame, said lower sash formed with a flared portion upon the upper portion thereof, said flared portion being formed with ratchet notches 90 thereon, and means hingedly mounted upon said frame adapted to close the space between the outer extremity of said flared portion and the lower end of said upper sash.

In testimony whereof I affix my signature 95 hereto.

THOMAS O'FLYNN.
